UNITED STATES PATENT OFFICE.

MINOR F. H. GOUVERNEUR, OF BALTIMORE, MARYLAND, ASSIGNOR TO LOCKE INSULATOR CORPORATION, OF BALTIMORE, MARYLAND, A CORPORATION OF MARYLAND.

DEVICE FOR CUTTING HOLES IN INSULATORS.

Application filed November 20, 1925. Serial No. 70,429.

This invention relates to devices used in the making of insulators, particularly those of the Hewlett type having interlinking curved passages therein for the reception of suspension elements.

The object of the invention, generally stated, is to provide a device adapted to be disposed upon a molded insulator while still in a plastic condition, the device embodying cutting means whereby the material of the insulator may be cut out to define the necessary curved passages.

The object of the invention, more specifically stated, is to provide a device of this character adapted to be disposed upon an individual insulator and carrying selectively usable supporting and guide means for successively usable cutters whereby separate but adjacent cuts may be made to define the desired curved passage, one cutter forming the inner wall thereof and the other the outer wall, it being preferable that the passages be narrowest at their central portions with their end portions flaring in order that in case of freezing of water accumulating therein expansion may occur without danger of breakage.

Another object of the invention is to provide means of this character in which the same type of shiftable support, guide and cutters are used for working upon the insulator from the top or underside thereof inasmuch as the interlinking curved passages open out to the opposite sides of the insulator.

Still another object is to provide a device of this character in which the relatively stationary support carries stop means for limiting movement of the movably mounted guide support or carrier so that the selectively usable cutters will be brought into the proper position for making the necessary cuts.

A further object of the invention is the provision of cutting means which may be identically the same for use at the top and bottom of the insulator with the exception of variations in the shape or size of the relatively stationary support whereby the support may be easily centered with respect to the insulator.

Another object is to provide cutting means, the construction and operation of which will be such as to make a clean cut at the point where the cutting tool emerges from the in-

sulator, tearing of the plastic material being consequently avoided.

The invention further contemplates the employment of a cutter of tubular form, which when forced through the insulator will retain the material cut therefrom, the cutters used being, moreover, removably mounted upon their guides and being consequently readily capable of removal for cleaning purposes and replacement in case of necessity.

Another object of the invention is the provision of a cutter guide so constructed as to engage the cutter at only three spaced points whereby an adequate support will be provided while frictional resistance to sliding of the cutter upon the guide, under manual impulse, will be reduced to the minimum, the work being consequently lightened.

To the attainment of the foregoing and other objects and advantages such as simplicity, cheapness, ease of manipulation and the general improvement of the art, the invention preferably consists in the details of construction and the arrangement and combination of parts to be hereinafter more fully described and claimed, and illustrated in the accompanying drawings wherein:

Figure 1 is a plan view of the cutter in operative position upon the top of an insulator,

Figure 2 is a cross section taken on the line 2—2 of Figure 1,

Figure 3 is a cross section taken at right angles to Figure 2,

Figure 4 is a cross sectional view showing the form of device used for cutting the insulator from the underside thereof, the smaller cutter being shown in action.

Referring more particularly to the drawings the letter A designates a suspension insulator of the Hewlett type formed in the usual or any preferred manner and having an upstanding central portion B, a central lower portion C and a depending skirt D. The top surface E outwardly of the central upstanding portion B is represented as sloping slightly downwardly and outwardly. In insulators of this type it is customary to provide interlinking curved passages shown at F and G for the reception of suspension devices, not shown, which passages are formed by the means to be described.

In carrying out the present invention I provide a relatively stationary support 1 here

shown as of disk-like form and of a diameter the same as or slightly less than the maximum diameter of the insulator, which support is intended to be disposed upon the top of the insulator, the central portion of the supporting disk being cut away as indicated at 2 so as to accommodate the central upstanding portion B, the disk itself lying upon and preferably conforming to the top surface E of the insulator. Secured upon the support or disk 1 and located at opposite sides of the opening 2 therein are spaced guides 3 arranged in pairs. While these guides might have any preferred specific construction they are here represented as consisting of or including strips 4 upon which are secured strips 5 which overhang the confronting edges of the strips 4 and constitute retaining means for the relatively movable support 6 which is represented as being of curved shape in cross section and terminating at its side edges in flanges 7 engaged beneath the overhanging strips 5. The curvature of the support 6 is such that it will clear the central upstanding portion B of the insulator to avoid injuring the surface thereof. At spaced points intermediate its length the relatively movable support 6 is formed or otherwise provided with guides 8 and 9 both of which are concaved and of partial ring-like form. While both guides are arcuate, they are eccentric with respect to each other, the guide 9 being of less diameter than the guide 8 and having its center substantially concentric with the center of curvature of the upper surface of the upstanding central portion B of the insulator. The curvature of the guide 8 is such that its center coincides with the center of the curvature of the lower surface of the depending central portion C of the insulator. The guides 8 and 9 may conveniently be of the skeleton-like construction shown in the drawings. Furthermore, these guides terminate, at one end, considerably above or spaced from the relatively stationary support or disk 1 while at their other ends they extend into the cut away portion 2, this latter mentioned detail being illustrated in Figures 2 and 4.

The apparatus further includes cutters 10 and 11, the former of which is used in connection with the guide 8 and the latter of which is used in connection with the guide 9. Each of these cutters is shown as being of tubular material and of the shape, substantially, of a half ring. The cutters are concentric with respect to the guides 8 and 9 and, when ready for use, are fitted into the concavities in the guides. The cutting action involves movement of the cutters along the guides, as will be described, and for these reasons the concavities in the guides are preferably of such cross sectional configuration that only the edges and the bottoms will be engaged by the cutters, thus greatly reducing

friction as there are only three lines of contact. Secured upon one end of the cutter 11 is an elongated strip 12 constituting a handle, while the cutter 10 is preferably provided with a loop-like handle 13 which may, in actual practice, be cut from the material of the cutter itself and formed into the desired shape, though naturally such details are immaterial.

During the operation which will be explained it is necessary that the relatively movable support 6 be shifted to bring one cutter and then the other, into cutting position at the center of the insulator, for which reason the above described slidable feature is provided. For limiting the movement so as to insure the bringing of the cutters into the exact positions desired, it is preferable to provide stops 14 and 15, the former of which will be engaged by the slidable support 6 when the cutter 11 is in operative position, and the latter of which will be engaged by the slidable support when the cutter 10 is in proper position for cutting.

In the operation, the disk 1 is centered upon the top of the insulator and the support 6 is slid to one limit of its movement to bring either the cutter 10 or the cutter 11 into active position. Assuming that this has been done and that the parts are in the position shown in Figures 1 and 2, the operator engages the cutter 10 upon the guide 8 and, grasping the handle 13, moves the cutter along, upon or about its guide, in the direction of the arrow in Figure 2 so that the cutter will be forced, in a curved path, through the material of the insulator, thus forming the outer wall of the curved passage F. Obviously the material cut remains within the cutter and may subsequently be removed therefrom by pushing it out by any suitable means such for instance as a flexible rod or its equivalent. When the end of the cutter is about to emerge from the insulator, a soft rubber pad or the like may be pressed over the point of emergence so that the cutter will make a clean cut instead of tearing away the material. After the first cut has been thus made, the cutter 10 may be laid aside and the slidable support 6 is shifted into its other position to bring the guide 9 over the center of the insulator. The cutter 11 is then applied and used on the guide 9 in exactly the same manner as described in connection with the cutter 10 in order to make a cut merging into the first cut and defining the inner or more abruptly curved wall of the passage F.

In forming the passage G through the upper portion of the insulator, an equivalent device is used, all the parts being identically the same except that the above described disk 1 is replaced by a similar disk 16 which is of smaller diameter so as to fit within the confines of the skirt D and against the underside of the insulator between the skirt and the

depending projection C. Any supporting means may be provided upon which the insulator itself is laid in inverted position. The same operation of cutting with one cutter, 5 shifting the slidable support and then cutting with the other cutter is gone through with as above described in order to form the passage G which is of exactly the same size and shape as the passage F but at right angles thereto so 10 that the two passages will interlink as is necessary.

A feature of importance is the fact that the opening 2 in the support 1 and the corresponding opening 17 in the supporting disk 16 are 15 of such shape as to accommodate, respectively, the upward and downward projections at the central portion of the top and bottom surfaces of the insulator, the openings thus serving as a guide to insure the disposition of the disks 20 1 and 16 in such positions that the passages cut will be at right angles to each other as is requisite in this type of insulator. Obviously any suitable auxiliary tools or other devices may be used or any methods may be resorted to for smoothing off the edges at the 25 ends of the interlinking passages, though this is a detail not illustrated, as being of minor importance.

A cutting apparatus constructed in accordance with this invention will be inexpensive to make and easy to operate, the latter feature being of great importance inasmuch as a large number of insulators may be quickly and accurately cut without requiring any 35 great degree of skill, the cost of production being consequently materially reduced and the danger of ruining insulators during the cutting operation greatly decreased.

While I have shown and described a preferred embodiment of the invention, it should be understood that the disclosure is merely illustrative as the right is reserved to make many changes in the details of construction and also in the arrangement and combination 45 of parts so as to widen the field of utility and increase the adaptability of the invention, provided, of course, that such variations constitute no departure from the spirit of the invention or the scope of the claims hereunto 50 appended.

Having thus described the invention, I claim:

1. In a device of the character described, a relatively stationary support adapted to be disposed upon an insulator in plastic condition, 55 said support having an open portion exposing the material of the insulator, a guide carried by the support, and a cutter movably mounted upon the guide and movable through said open portion and along a curved path through the material of the insulator to form a curved passage therein.

2. In a device of the character described, a relatively stationary support adapted to be disposed upon an insulator in plastic condi- 60

tion, said support having an aperture therein exposing the insulator, a guide carried by the support, and a cutter movably mounted upon the guide and adapted to pass through said aperture, said cutter being movable along a curved path through the material of the insulator to form a curved passage therein, the cutter being removably mounted upon the guide. 70

3. Means for cutting curved passages in insulators, comprising a relatively stationary support adapted to be engaged upon an insulator, said support having an open portion, a support movably mounted upon said relatively stationary support and carrying 80 guides, and selectively operable cutters of curved formation carried by the guides and movable therealong and into and through the material of the insulator. 75

4. Means for cutting curved passages in insulators in a plastic condition, comprising a relatively stationary support adapted to be centered with respect to an insulator and having an open portion exposing the material of the insulator, a relatively movable support 85 slidably mounted upon the relatively stationary support, guides on the movable support, curved tubular cutters slidably mounted on said guides and movable through the material of the insulator, and means for positively positioning a selected guide and cutter 90 at the center of the insulator. 95

5. Means for cutting curved passages in insulators in a plastic condition, comprising a relatively stationary support adapted to be 100 centered with respect to an insulator and having an open portion exposing the material of the insulator, a relatively movable support slidably mounted upon the relatively stationary support, guides on the movable support, curved tubular cutters slidably mounted on said guides and movable through the material of the insulator, and means for positively positioning a selected guide and cutter 105 at the center of the insulator comprising stops 110 on the relatively stationary support engageable by the movable support. 110

6. In an apparatus of the character described, a relatively stationary support adapted to be centered with respect to an insulator, 115 guide means movably mounted with respect to the stationary support, cutting means movably mounted upon the guide means and rotatable thereabout to pass through the material of the insulator for forming a curved passage therein. 120

7. Means for cutting a curved passage through an insulator in plastic condition, comprising a relatively stationary support adapted to be centered upon an insulator, a 125 pair of guides, means for shifting the position of the guides with respect to said support and the insulator to bring a selected guide at the center of the insulator, selectively and successively usable cutters disposable 130

upon said guides and rotatable thereabout to pass through the material of the insulator, said cutters being of curved form and one being eccentric with respect to the other whereby the holes cut thereby will merge and define a curved passage having walls of different curvature.

8. In a device of the character described, supporting means adapted to be centered upon an insulator, a plurality of guide members movably mounted upon said supporting means, cutters movably mounted upon the respective guide members, the cutters being of curved tubular form and adapted to be moved along the guide members into and through the material of the insulator, said cutters having different curvatures.

9. In a device of the character described, supporting means adapted to be centered upon an insulator, a plurality of guide members movably mounted upon said supporting means, cutters movably mounted upon the respective guide members, the cutters being of curved tubular form and adapted to be moved along the guide members into and through the material of the insulator, said cutters having different curvatures and one being eccentric with respect to the other.

10. In a device of the character described, a support adapted to be centered upon an insulator in contact therewith, the support having an open central portion, a movable support slidably mounted upon the stationary support, means for limiting the sliding movement of the movable support, curved guide members carried by said movable support selectively disposable over the center of the insulator, and substantially semicircular tubular cutters removably mounted upon the guides and movable therealong through said opening to cut through the material of the insulator and to retain the cut material.

11. In a device of the character described, a support adapted to be centered upon an insulator in contact therewith, the support having an open central portion, a movable support slidably mounted upon the stationary support, means for limiting the sliding movement of the movable support, curved guide members carried by said movable support selectively disposable over the center of the insulator, and substantially semicircular tubular cutters removably mounted upon the guides and movable therealong through said opening to cut through the material of the insulator and to retain the cut material, said guide members having channeled peripheries of irregular curvature in cross section providing bearing points for the cutters.

12. A device for forming holes in insulators of the Hewlett type while the insulators are in a plastic state, comprising a relatively stationary supporting member adapted to be engaged against the top or bottom of the insulator to be cut, means for centering the sup-

porting member with respect to the insulator, said supporting member having an aperture therein exposing the material of the insulator, curved guide means on said supporting member, and a cutter slidably mounted along said guide means and adapted to be moved through the aperture and the material of the insulator for forming a curved passage.

13. Means for cutting insulators of the Hewlett type having curved projections at the top and bottom thereof while the insulators are in a more or less plastic condition, comprising a supporting member adapted for disposition against a flat surface of the insulator and having an open portion accommodating the curved projection at said flat side and exposing the material of the insulator, means for centering the supporting member with respect to the insulator, and selectively operable cutters movable with respect to the supporting member and adapted to pass along a curved path through the material of the insulator for producing the curved passage therein.

14. Means for cutting insulators of the Hewlett type while in a plastic condition, comprising selectively usable supporting means adapted for disposition against the top or bottom surface of the insulator to be cut, each supporting member having an open portion exposing the material of the insulator, a movable member shiftably mounted with respect to either guide employed, guides of different sizes and eccentrically related carried by said relatively movable member, means for maintaining the relatively movable member at a selected position with a selected guide located at the diameter of the insulator, and selectively usable cutters adapted for sliding movement along the corresponding guide and adapted to move through the open portion and through the material of the insulator.

15. In an apparatus of the character described, a relatively stationary support adapted to be centered with respect to an insulator, guide means adapted to be disposed at the center of said relatively stationary support, and cutting means detachably engageable upon the guide means and movable therealong to pass through the material of the insulator for forming a curved passage therein.

16. In an apparatus of the character described, a relatively stationary support adapted to be engaged upon an insulator against the top or bottom surface thereof and having an opening exposing the material of the insulator, selectively usable curved guide means disposable at the center of the relatively stationary support, selectively usable cutting means engageable upon the guide means and movable therealong to pass through the material of the insulator in a curved path.

17. In a device of the character described, a relatively stationary support adapted to be centered with respect to the top or bottom of an insulator in plastic condition, a relatively movable support slidable along said relatively stationary support and provided with lateral flanges, retaining members on the relatively stationary support overhanging said lateral flanges, curved guide members on said 10 relatively movable support disposable selectively at the diameter of the insulator, stops on the relatively stationary support engageable by said relatively movable support for limiting its movement in both directions, and 15 curved cutting means adapted to be engaged upon the respective guide means and movable therealong to pass through the insulator in a curved path.
18. In a device of the character described, a support adapted to be centered with respect to an insulator of the Hewlett type, a plurality of successively usable cutting means movably mounted with respect to the support along curved paths of different radii for forming passages in the insulator. 20 25
19. In a device of the character described, a support adapted to be centered with respect to an insulator of the Hewlett type, a plurality of successively usable cutting means movably mounted with respect to the support along curved paths of different radii for forming passages in the insulator, and guide means for the respective cutting means disposable at the diameter of the insulator. 30

In testimony whereof I affix my signature.

MINOR F. H. GOUVERNEUR.
